APPARATUS FOR APPLYING TREATING LIQUIDS TO FIBERS

Hughes L. Siever, Keyser, W. Va., assignor to
Borne Scrymser Company, a corporation of New Jersey

Application June 26, 1944, Serial No. 542,197

4 Claims. (Cl. 68—205)

1

This invention relates to a method and means for applying a conditioning liquid such as lubricants, dyes, tints, hydroscopic agents, and the like to textile stocks and particularly the application of oil or dyestuff or any conditioning agent to raw textile stocks or textile blends in the course of manufacture in the normal sequence of operations incident to the finished product.

According to my invention, the stock is treated while in lap or mass form and is subjected to the conditioning liquid by having the liquid deposited on the moving fibers in the form of fine droplets by means which are oscillated and vibration imparted thereto so as to divide the drops into small globules, and depositing the same onto the travelling mass of fibers as it advances.

I accomplish the application of the liquid to the moving textile fibers by conducting the liquid to a reservoir pipe disposed transversely of the travelling mass of fibers and feed the conditioning liquid through a plurality of nozzles extending from said reservoir or openings in the top portion of the reservoir and impart oscillation and vibration to said reservoir pipe so as to shake the drops from the nozzles or projections and to break them up into many fine droplets to cast them onto the fibers travelling thereby.

Some of the objects of the invention having been stated, other objects will appear as the description proceeds when taken in connection with the accompanying drawings, in which:

Figure 1 is a side elevation of a portion of a picker showing my invention mounted thereon;

Figure 2 is a transverse sectional view taken along the line 2—2 in Figure 1;

Figure 3 is a vertical sectional view taken along the line 3—3 in Figure 2;

Figure 4 is a top plan view taken along the line 4—4 in Figure 2;

Figure 5 is a vertical sectional view along the line 5—5 in Figure 2;

Figure 6 is a view similar to Figure 2, but showing another form of the reservoir pipe;

Figure 7 is a cross-sectional view taken along the line 7—7 in Figure 5;

Figure 8 is a longitudinal sectional view of the reservoir pipe;

Figure 9 is an elevation of a short section of a modified form of the reservoir pipe;

Figure 10 is a longitudinal section through the form of reservoir pipe shown in Figure 9.

In the conventional picker 9, illustrated in the drawings, the stock 10 is supported on a conveyor 11 and by it is continuously advanced towards a beater chamber 12 in which a conventional beater, not shown, is disposed for engaging the stock and beating the same.

It will be understood that the term "lap" is used herein, not in its limited sense to denote only the finished lap, but to include also the sheet, mass or

bat form at various points in its course to and through the picking and opening machinery.

Mounted on the upper frame members 14 and 15 of the picker are standards 16 and 17 having bearings 18 and 19 thereon in which is mounted for oscillation a pipe 20. This pipe 20 has suitable fins 21 on each side thereof which are adapted to work in suitable grooves in bearing 18, for example to prevent turning movement of the pipe. The pipe 20 has rising from the top surface thereof a plurality of inverted U-shaped nozzle members 25 which project upwardly, then laterally, and then downwardly, and have a restricted nozzle portion 26. In Figure 1, these pipes 25 are shown as one piece, and in this form would be welded or brazed to the main pipe 20; whereas in Figure 3, for example, instead of having the inverted U-shaped pipes 25, there is provided a vertically disposed reservoir pipe 30 having its lower end threadably secured in the pipe 20, and having its upper end closed by a cap 31 and having threadably secured in one of its side walls an L-shaped pipe 32 whose lower end is restricted as at 26 for allowing the oil, dye, or other conditioning fluid to drip therefrom in the form of droplets.

The ends of the pipe 20 are closed by suitable cap members 35 and 36 and between the bearing 19 and cap 36 is a compression spring 37 which normally tends to move the pipe to the right in Figure 2 to where the cap 35 will rest against bearing 18. This pipe 20 is adapted to be oscillated by means of an electric motor 40 being mounted on the frame and adapted to be driven by any suitable source of electric current through wires 41 and 42. This electric motor has a motor shaft 43 which enters a gear reduction box 44 and from gear reduction box 44 a shaft 45 is provided which has a cam 46 on its upper end adapted to engage the cap 36 and to impart oscillation to the pipe 20 by pushing the pipe all the way to the left in Figure 2 until the high point 50 of the cam 46 is reached, at which time, the compression spring 37 will quickly move the pipe 20 to the right in Figure 2 until its cap 35 engages bearing 18 which will suddenly stop the pipe 20 and cause any drops emanating from the restricted portions 26 to be broken up into fine droplets and cast upon the travelling lap of cotton 10. These vibrations can be as many per minute as desired in order to properly break up the drops of conditioning liquid or dye into droplets.

Leading from and connected to pipe 20 is a flexible tube 51 which is connected to a flow control and manually operated valve 52, and the other side of the valve 52 is connected to a solenoid or other shut-off valve 53 whose wires 54 and 55 are connected to the same electric current as electric motor 40 or to an independent source as drives the textile machinery.

2

The oscillating motion may be obtained by independent motor or a mechanism synchronized with the textile machine movements so that the flow can be started and stopped by valve 53 when the machine starts or stops.

Leading from valve 53 is a pipe 56 which is connected to an elevated tank 57, which serves as a source of supply or, if desired, pipe 56 may be supplied by a force feed as for instance a pump leading to a suitable source of supply.

The flow control valve 52 can be adjusted to allow the desired amount of liquid to flow into reservoir pipe 20. The reservoir pipe 20 is full at all times and rises into pipes 25 and to nozzles, then drops down the vertical portion of the pipes 25 and out through openings 26. On account of this feature, when the valve 53 is closed, or the flow control valve 52 should be closed, since there is no appreciable amount of liquid present in the pipe 51, it is thus seen that the flow of liquid through the nozzles 26 will stop almost immediately upon stoppage of the textile machine, and thus no great amount of liquid will be deposited onto the mass of fibers 10.

If desired, any liquid can be applied with satisfactory results by operating the pipe 20 while stationary, that is, allowing it to stand in normal position, but I believe that better results are obtained by vibrating the apparatus and giving frequent jars thereto to detach the drops of liquid from the nozzles thus breaking them into finer droplets than if the liquid is allowed to drop onto the lap of moving fibers 10 without vibrations for the reason that the drops of conditioning liquid are evenly distributed through the mass by mechanical contact after it passes through the mechanical beating chamber 12, because there the fibers are disintegrated and formed into a new combination and those fibers which have a greater amount of fluid thereon impart the liquid to other fibers with a lesser amount thereon, and thus the fluids are evenly distributed as it is beaten immediately after being deposited onto the moving web 10.

In Figures 6-10 inclusive, there is shown a modified form of the reservoir pipe designated as 20a. In Figure 6, much of the structure is similar to the structure shown in Figure 2, and like reference characters will apply. However, in this modified form of the invention instead of having the upwardly, laterally, and downwardly extending nozzle pipes 25, I have shown the reservoir pipe 20a with a plurality of circumferential grooves 60 and coinciding with the top portion of each of these grooves 60 and at the uppermost part of the reservoir pipe 20a, there is a perforation or hole 61 and in the bottom of the reservoir pipe 20a, there is secured a solid plug 62 which is pointed at its lower end so that the treating liquid will flow out of the openings 61 and be directed downwardly by the circumferential grooves 60 onto the plugs or teats 62 which being pointed at their lower ends causes the drops to collect on the points and to be more easily shaken therefrom. While these plugs 62 are shown threadably mounted in the pipe 20a, and having a squared portion 63, to be engaged by a wrench, it is evident that they could be welded onto the pipe 20a or cast integral therewith as evidenced by the teats 64 as shown in Figures 9 and 10. Such pipe 20a would also

have circumferential grooves 60 and openings 61 as previously described.

In the drawings and specification, there has been set forth a preferred embodiment of the invention and although specific terms are employed, they are used in a generic and descriptive sense only, and not for purposes of limitation, the scope of the invention being defined in the claims.

10 I claim:

15 1. Apparatus for applying a treating liquid to a horizontally moving lap or mass of fibers which comprises a pipe disposed in spaced relation above the moving mass, the longitudinal axis of the pipe being at right angles to the path travelled by the fibers, said pipe having a plurality of outlets and means for supplying the treating liquid to these apertures with sufficient head for it to flow out of the open ends of said 20 apertures, and means for imparting blows to the pipe intermittently to shake the drops of liquid from the apertures onto the moving lap.

25 2. Apparatus for applying a treating liquid to textile stocks traveling in a substantially horizontal direction through a machine, comprising in combination with textile machines, a pipe disposed above and transversely of the direction of movement of the stock and being movable laterally of the direction of travel of the stock and having a plurality of nozzles disposed above and spaced from the stock for dropping the liquid onto the stock, means for regulating the flow of the liquid into the pipe, an electrically controlled valve for stopping flow of liquid to the reservoir and means for imparting blows to the pipe to jar the liquid from the nozzles.

30 3. Apparatus for applying a treating liquid to textile stock traveling in a substantially horizontal direction through a textile machine comprising in combination substantially horizontally disposed means for supporting and moving a flat lap of stock, a reservoir pipe disposed above and transversely of the direction of movement of the stock and having a plurality of nozzles disposed in spaced relation from the stock for dropping the liquid onto the stock, means for regulating the flow of the liquid into the pipe, an electrically controlled valve for stopping flow of the liquid into the pipe, and means for imparting blows to the reservoir pipe to jar the liquid from the nozzles and to break it into fine particles for depositing onto the stock.

40 4. In a textile machine having substantially horizontally disposed means for moving a mass of fibers therethrough, a pipe disposed transversely above the mass of fibers and having a plurality of openings therein in spaced relation to the mass of fibers, means for supplying a liquid to said pipe so the liquid will flow through said openings and drop by gravity onto the moving mass of fibers, means for mounting the pipe for endwise movement, spring means for urging the pipe endwise in one direction, means for limiting said endwise movement against the pressure of said spring means and releasing the pipe to allow the spring means to return the pipe to original position to suddenly stop endwise movement of the pipe to thus jar drops of liquid loose from the openings.

HUGHES L. SIEVER.
